(57) **CLAIM**

The ornamental design for a spool, as shown and described.

DESCRIPTION

FIG. 1 is a perspective view of a spool of the present invention;

FIG. 2 is a top view of the spool of FIG. 1;

FIG. 3 is a front side view of the spool of FIG. 1, the left, right and rear side views being identical; and,

FIG. 4 is a bottom view of the spool of FIG. 1.

The broken lines in the drawings illustrate portions of the spool which form no part of the claimed design.
